UNITED STATES PATENT OFFICE.

PETER DAUGERT, OF WILKES-BARRE, HENRY FREY, OF KINGSTON, AND JOHN J. DUNLEAVY, OF PLYMOUTH, PENNSYLVANIA.

BRACKET FOR THREAD CLEANERS.

Application filed June 30, 1927. Serial No. 202,505.

This invention relates to improvements in thread cleaning devices, and has particular reference to brackets therefor especially adapted for use with thread cleaning plates 5 such as disclosed and claimed in our former Patent No. 1,625,352, dated April 19, 1927.

An object of the present invention is to provide an improved bracket for supporting cleaner plates, which is of simple, practical 10 and inexpensive construction and which is so made that it can be applied to various types of apparatus and machines employed in winding threads and positioned relative thereto in such a manner as to effect the highest 15 degree of efficiency in the thread cleaning operation.

Another object is to facilitate the mounting of cleaning plates in the bracket so that the same will be properly positioned therein 20 with respect to each other and to the thread being cleaned, and maintained in such position during the cleaning operation.

The above and other objects will appear more clearly from the following detail description, when taken in connection with the accompanying drawings, which illustrate preferred embodiments of the inventive idea.

In the drawings—

Figure 1 is a fragmentary elevation, partly in section, of one form of the invention, showing the same in operative position on a skein winding mechanism;

Figure 2 is a fragmentary front elevation of Figure 1;

Figure 3 is a section taken on the line 3—3 of Figure 1;

Figure 4 is a front elevation of another form of the bracket mounted on a steel rod;

Figure 5 is a side elevation, partly in section, showing the manner in which the bracket is mounted on the rod;

Figure 6 is a section on the line 6—6 of Figure 4;

Figure 7 is a view similar to Figure 5, illustrating the manner in which the bracket is mounted on a metal or wooden bar;

Figure 8 is a section on the line 8—8 of Figure 7;

Figure 9 is a view similar to Figure 5, illustrating the application of the bracket to an angle iron; and

Figure 10 is a section on the line 10—10 of Figure 9.

The brackets of the present invention have 55 been designed particularly with the end in

view of making the same applicable to various types of machines, such as winders, redrawers, quillers, coppers, coners, reels and the like, and although the brackets are particularly adapted for use in connection with cleaning plates such as disclosed in the above mentioned patent, it will be understood that said brackets may also be employed with other cleaning plates known in the art.

In Figures 1 and 2, the application of one form of bracket to a winder mechanism is shown and this form of the invention may also be applied to redrawers. In said figures the numeral 11 indicates a swift upon which the skein of thread 12 to be cleaned is wound, said thread being fed from said swift over the usual traverse bar 13 which reciprocates in front of a plurality of bobbins, one of which is indicated at 14 and driven by means of the wheel 15 rotatably mounted on a common driving shaft 16.

The bracket of the present invention is constructed so that it can be supported by the traverse bar 13 in order to be movable therewith as the thread is being wound back and forth upon the bobbin 14. Further, it is to be noted that the bracket is supported from the underside of the traverse bar and extends diagonally downward therefrom. This is done in order to dispose the weight of the plurality of brackets, which are usually attached to the traverse bar, as nearly as possible in a direct line below said bar to avoid tilting thereof which might otherwise occur and which would result in a defective operation of said bar. The arrangement of the bracket as shown also permits of the thread passing between the cleaner plates at the proper angle which will produce the most efficient operation and cleaning of the thread.

The bracket as shown comprises a central substantially rectangular plate supporting portion 17 having an opening 18 extending therethrough which is of a size to snugly receive the cleaning plates 19 adjacent ends of which project on opposite sides of the portion 17 when said plates are properly positioned in the bracket. Projecting from one side of the portion 17 is an extension 20 one surface of which is in a plane with one wall of the opening 18 so that the portions of the plates 19 which project from said side of the portion 17 will abut against said surface of the extension 20. To limit the movement 110

of the plates 19 as they are being inserted into the portion 17 from the side thereof opposite the extension 20 and to thereby properly position said plates in the bracket, said extension 20 is provided at its free extremity with a laterally projecting stop 21 having angularly disposed surfaces 22 against which the angular guide surfaces of the plates 19 engage, as clearly shown in Figure 3. After the plates have been so inserted into the bracket they are fixed in their operative positions by means of a screw 23 countersunk in one face of the portion 17 and provided in its outer end with a key opening 24 into which a suitable key may be fitted to thread the inner end of the screw into binding engagement with the adjacent edge of one of the cleaner plates 19. This screw not only enables the plates to be easily and rapidly secured in their operative positions, but also allows them to be quickly detached from the bracket and their positions changed or replaced by other plates in accordance with the invention set forth in the aforementioned patent.

Extending at right angles from one face of the portion 17 and extension 20 is a supporting arm 25 which may be tapered as shown in Figure 2, and this arm is provided adjacent its free extremity with an opening for receiving the screw 26 of a thread guide 27 having a central thread receiving slot 28, the entrance end of which is overlapped by the two oppositely projecting retaining hooks 29. Although it is preferable to use this kind of a guide, it will be understood that other types may be also employed. A nut 30 may be threaded on the screw 26 and engaged with the arm 25 to retain the guide in its operative position. It is desirable that the arm 25 be of such a length that the guide 27 is spaced from the cleaning plates a sufficient distance to enable the proper manipulation of the thread and the removal of waste, dirt, etc. from said plates. The proper spacing of the guide 27 from the cleaning plates 19 will also dispose said guide at such a distance from the skein of silk being unwound as to effect a most efficient operation and reduce as much as possible the friction on the thread 12.

On the face of the portion 17 opposite that from which the arm 25 extends, there is formed a second supporting arm 31 offset relative to the portion 17 and provided with an upper bearing surface which abuts against the lower edge of the traverse bar 13 when the bracket is suspended therefrom in proper position. One edge of the arm 31 is provided with the lugs 32 which engage the back of the traverse bar as shown in Figure 1. Said arm 31 is further provided therein with a slot 33 through which may be extended a screw 34 for the purpose of securing the bracket to the traverse bar, said

slot permitting of limited longitudinal adjustment of the bracket relative to said bar.

An additional thread guide 35 is removably mounted upon the top edge of the traverse bar 13 and held in position thereon by the springs 36, the eye of said guide being in alignment with the slot formed between the inner edges of the plates 19 and also in alignment with the slot or eye 28 of the guide 27.

In the form of the invention shown in Figures 4 to 6, the portion 17, extension 20, and arm 25 of the bracket are precisely the same as that above described. Instead of the offset arm 31, the present embodiment is provided with an arm 37 of the same formation as the arm 25 and extending directly from the face of the portion 17 opposite that carrying said arm 25. Both of the arms 25 and 37 may, in this instance, carry the thread guides 27, the eyes of which are aligned with the slots formed by the plates 19. With this form of bracket wherein the extension 20 and the arm 25 are again at right angles to each other, the device is adapted to be mounted upon various shaped members on different types of machines. As illustrated in Figures 4 to 6, the bracket is mounted in position upon a rod 38 by employing a block 39 secured to said rod by the screw 40 and fitting into the angle formed by the extension 20 and arm 25, the bracket being in turn secured to said block by a screw 41.

In Figures 7 and 8, the bracket is illustrated as being mounted upon a rectangular bar 42, which may be of metal or wood and which also fits into the angle formed by the parts 20 and 25, the bracket being secured in position on the bar by the screw 43.

Another manner of mounting this universally adaptable bracket is shown in Figures 9 and 10, wherein the bracket is attached to an angle iron 44 by the screw 45. Thus it will be seen that the brackets shown in the different figures of the drawings are, by reason of their peculiar novel construction, capable of being mounted upon several different types of machines and members thereof, and further that the bracket provides a simple and highly efficient means for supporting and retaining the thread cleaning plates in operative position relative to the thread being cleaned.

What is claimed is:

1. A bracket for thread cleaners including a cleaner plate-supporting portion having an opening therein for receiving cleaner plates, an extension projecting from said portion and having a surface in a plane with and forming a continuation of one wall of said opening and upon which said plates are supported when inserted through said opening, thread guide-supporting arms extending from opposite sides of said portion and at the inner end of said extension, and a stop

formed on said extension at the outer end thereof against which abut the adjacent ends of said cleaner plates.

2. A bracket for thread cleaners including a cleaner plate-supporting portion having an opening therein for receiving cleaner plates which have their ends formed at an angle to each other, an extension projecting from said portion and having a surface in a plane with and forming a continuation of one wall of said opening and upon which said plates are supported when inserted through said opening, thread guide-supporting arms extending from opposite sides of said portion and at the inner end of said extension, and a stop formed on said extension at its outer end and having angularly disposed surfaces engageable by the angular ends of said cleaner plates.
- 10 3. A bracket for thread cleaners including a cleaner plate-supporting portion having an opening therein for receiving cleaner plates, an extension projecting from said portion and with which said plates are engageable when in position in said opening, and a
- 15
- 20
- 25

thread guide-supporting arm projecting laterally from one side of said portion and combining with said extension to form an angle, the sides of which are adapted to engage an angular member fitted into said angle and to which the bracket is attachable.

4. A bracket for thread cleaners including a cleaner plate-supporting portion having an opening therein for receiving cleaner plates, an extension projecting from said portion and with which said plates are engageable when in position in said opening, and a thread guide-supporting arm projecting from one side of said portion and combining therewith to form a right angle on the side of said arm opposite that on which a thread guide is carried, said right angle being adapted to receive an angular member to which the bracket is to be attached.

In testimony whereof we have affixed our signatures.

PETER DAUGERT.
HENRY FREY.
JOHN J. DUNLEAVY.
